LABELING MACHINE

George M. Biner, Los Angeles, Calif.

Application June 19, 1937, Serial No. 149,123

14 Claims. (Cl. 216—54)

My present invention relates to labeling machines and more particularly to a labeling machine having a minimum of parts and a relatively light, open frame that permits the operator to closely watch every phase of the operation of the machine. This application is an improvement upon the machine shown and described in my pending application for patent Serial No. 131,273, filed March 17, 1937, to which reference is made for subject matter shown but not claimed herein.

An important object of my invention is to provide a machine for the mechanical labeling of containers wherein the cost of manufacture is greatly reduced by the use of a light rectangular frame and the use of simple swinging parts. The use of costly cams and associated parts is held to a minimum in my machine.

A further object is to provide a holder for labels that is normally out of reach of the picker bars, to avoid having to stop the machine when the supply of containers is temporarily exhausted.

Another object is to provide an adhesive transfer roll that is held in uniformly close contact with the picker bars during the adhesive transfer period.

My improved machine provides other objects and advantages due to the novel combinations and arrangements of parts that will be more fully apparent in the course of the following description.

In the drawings, like reference characters designate similar parts in the several views.

Figure 1 is a vertical section on the line 1—1 of Figure 3.

Figure 2 is a front elevation of the machine taken from the left of Figure 1.

Figure 3 is a horizontal section taken on the line 3—3 of Figure 1.

Figure 4 is a detail perspective view of a latch that holds the adhesive transfer roll in the position shown in Figure 1.

Figure 5 is a side elevation of the machine with parts broken away.

Figure 6 is a vertical section on the line 6—6 of Figure 3.

Figure 7 is a vertical section on the line 7—7 of Figure 1.

Figure 8 is a horizontal section on the line 8—8 of Figure 5.

Figure 9 is a fragmentary vertical section on the line 9—9 of Figure 3.

Figure 10 is a side elevation, partly broken

away, of a grip finger that holds the label against the container.

Figure 11 is a section on the line 11—11 of Figure 10.

Figure 12 is a vertical section taken on the line 12—12 of Figure 3.

Figure 13 is a side elevation of the parts shown in Figure 12, looking in the direction of the arrow A of the latter figure.

Figure 14 is a sectional view on the line 14—14 of Figure 13.

Figure 15 is a horizontal section taken through a bottle showing a label held in contact with the bottle by a grip finger and wipers.

Figure 16 is a side elevation, partly in section, of one of the wipers of Figure 15.

Figure 17 is a plan view of a modified form of label holder wherein an extra space is provided for neck labels.

Referring to the drawings in detail, the reference number 1 generally designates an open rectangular frame made, in the preferred embodiment, of channel iron and comprising vertical corner members 2, 3, 4 and 5, the same being connected by transverse bars 6 and 7 and tie rods 8, 9, 10, 11 and 12.

A channel bar 13 extends between corner members 2 and 4 as in Figures 1, 2 and 9. The channel 13 is perforated to receive rods 14, (see Figure 9), said rods being connected at their upper ends to a bottle supporting plate 15, spaced above the channel by spacers 16. A strap 17 extends across the rods 14 to hold the same in fixed position, after the rods have been adjusted to support plate 15 at the desired height. A bolt and nut, 18 and 19, fasten strap 17 to channel 13.

A pair of spaced rods 20 and 21, extend upwardly from plate 15 to hold the bottle B in labeling position, as in Figure 3. The rods 20 and 21 are provided with protecting sleeves 22 and 23, of rubber or other suitable material, to protect the bottle and at the same time leave its surface uncovered sufficiently for the label to be applied.

A label holder 24 is pivotally supported upon transverse shaft 25 by bearing 26. The label holder (see Figures 1 and 17), comprises a rectangular frame having a transverse bar 27 and angle iron support 28. The label holder is yieldably supported upon the frame members 6 by means of coil springs 29 and 30, positioned as shown in Figure 17.

Bar 27 and support 28 are connected adjacent their free ends by rods 31 and 32, said rods hav-

ing their ends threaded to receive nuts 33. The space thus provided is divided by transverse rods 34 having clamps 35 adjustably connected to rods 31 and 32, and longitudinal rods 36 adjustably fastened to rods 34. Upright angle strips 37 are adjustably fastened to the rods 36 and 34 by means of clamps 38.

The label holder 24 is pivotally supported upon bar 10 by means of an arm 39, pivoted to angle iron 28 at 40, said arm having a slot 41 to receive the bar 10. The arm 39 is in turn pivotally connected to a depending rod 42 which is releasably connected to a foot pedal (not shown). Thus it is seen that springs 29 and 30 normally hold the labels L out of reach of picker bars until the foot pedal is operated, making it unnecessary to stop the machine when a new supply of labels is being placed in position.

The lowermost ends of angle strips 37 are turned in as at 43 to support labels L, and the usual weight 44 is placed upon the same.

The modified form of label holder 24' provides an extra compartment 44 for neck labels L', by the addition of rods 34' and strips 37' on the rod 34' and on the adjacent rod 34. Otherwise the form shown in Figure 17 is similar to the first described form.

Means are provided to remove the lowermost label from the label holder 24, (see Figure 9), the transfer the same to bottle B, by the use of picker bars 45, provided with adjustable glue plates 46, and pivotally mounted on shaft 25. Fixed to shaft 25, between the picker bars and the frame parallel to the said bars, are cam bars 47 provided at their free ends with cams 48 for a purpose to be later described.

The glue plates 46 are supplied with glue by means of glue transfer roll 49 carried freely on shaft 50, which is mounted on the free ends of swinging arms 51, said arms are mounted on a shaft 55 which is journaled in bearings 52 above the frame member 6. Shaft 50 is also provided with cam rollers 53 mounted in alinement with cams 48 and adapted, as in Figure 9, to engage the same when a label is being removed from the label holder 24.

The transfer roll 49 is held in the position shown in Figure 1 by means of latches 54 pivotally connected to frame members 3 and 5, and actuated by means to be later described.

A glue pot or glue fountain 155 is mounted between frame members 3 and 5 by means of bearings 55 and 57 in which the shaft 58 is freely mounted. A glue pot roller 59 is mounted on shaft 58, and within glue pot 155, at a point opposite and somewhat higher than the bottle stand 15. A sprocket 61 is fixed to one end of shaft 58 and a clutch 62 is provided between roller 59 and the sprocket 61. A brace 163 is mounted on bar 11, aids in supporting the glue pot holder 164 which is provided with adjustable bolts 165. A hinged scraper plate 166 is mounted on the glue pot as shown in Figure 9.

In order to hold the label against the bottle after the picker bars have moved away from same, a grip finger 63 (see Figures 9, 10, 11 and 15), is provided. The grip finger is freely mounted on shaft 64 by means of strap 65 which is given a quarter turn to provide a guide bar for holder plates 66 which are turned in as at 67 to provide a dove-tail groove for a strip 68, which is made of rubber or other suitable material. A spacer bar 69 is riveted between plates 66 and coil springs 70 are set into alined recesses in bar 69 and strap 65. The plates 66 are yieldably connected to

straps 65 by means of rivets 71 extending into slots 72 of plates 66. Thus it may be seen that strip 68 is yieldably mounted on strap 65.

The strap 65 has a bracket lug 73 pivotally connected to link 74 which is yieldably connected by coil spring 75 to an arm 76 which is fixed to a rocker shaft 77.

As shown in Figure 15, padded fingers 78 are utilized to press the label against the bottle. The pressing fingers 78 swing on opposite sides 10 of the grip finger 63, and are preferably made of sponge rubber or the like. The sponge rubber pads of the fingers 78 are carried by box-like holders 79 which are yieldably connected by springs 80 and guide pins 81 to straps 82. Straps 82 are freely mounted on shaft 64, and are provided with depending lugs 83 which are pivotally connected to links 84. The links 84 are pivotally connected to arms 85 which are fixed to rock shaft 86.

The grip finger 63 is locked in its raised position (see Figures 10 and 15) by means of a latch comprising a pawl 87, fixed to shaft 77 and adapted to engage a pivoted arm 88. The arm 88, which is pivoted on frame member 4, is notched as at 89 and held against the pawl 87 by spring 90, carried by a bearing 91 also on the frame member 4. The arm 88 is released when engaged by pin 92, carried by a link 93, which is fixed to a shaft 86.

In order to operate the pressing fingers 78 at the proper time, a cam 94, (see Figure 7), is freely mounted on a shaft 95, which is supported by frame bars 7'. A cam roller 96 is carried by an adjustable arm 97 on a clamp 98, which is fixed to shaft 86.

The cam 94 is provided with an integral sleeve 99 having formed thereon a sprocket 100. The cam shaft 95 is provided at one end with a small sprocket 101 and at its other end with a large 35 sprocket 102.

My improved machine is driven by a motor 103, supported by arms 104 fixed to tie rod 9, as in Figure 5. Mounted on frame bar 7' is a shaft 105 provided with a large sheave 106 adapted to be driven from motor 103 by belt 107 at a reduced rate of speed.

The shaft 105 is provided at one end with a small sprocket 108, see Figure 6, so that a chain 109 may be utilized to drive sprocket 102 and 50 drive shaft 58 through the intermediary of sprocket 61. The cam sprocket 100 is connected by chain 110 to drive sprocket 111 on shaft 64.

Means for releasing latches 54, see Figure 6, is provided by a walking beam 112 fixedly mounted on shaft 25. One end of the walking beam is pivoted to an arm 113, which is provided with a lost motion slot 114, adapted to receive bolt 115 of a crank 16, fixed to shaft 77.

Fixed to shaft 64 is a crank 117 which is pivotally connected to the free end of walking beam 112 by a pitman 118. Short shafts 119 are mounted on the under side of frame bars 6, adjacent the latches 54, and fixedly support a rocker comprising lugs 120. The lugs have perforated extensions to receive rods 121 which extend through perforations 154 in latches 54, and plates 122 which are perforated to slidably receive rod 123. Rod 123 is pivoted to lug 124 of the walking beam 112 and has an adjustable stop 125 adapted to 70 contact one of the lugs 120 in order to release latches 54 by rocking the lugs 120, thereby lifting rods 121. The sprocket 101 on shaft 95 is connected by chain 126 to large sprocket 127 on shaft 75.

In the operation of my device, the bottle B or other container is placed upon the stand 15 and held against uprights 22 and 23, leaving an exposed surface between the same. As shown in Figure 1, the picker bars 45 having just picked a label and have moved into operative position adjacent the bottle. The picker bars are swung from the position shown in Figure 1 to that shown in full lines in Figure 9 by the rocking of shaft 25, which is fixed to walking beam 112, the same being actuated by the pitman 118 and crank 117. The crank 117 is rotated by shaft 64, driven by sprocket 127 and chain 128 from shaft 95. The shaft 95, see Figure 6, carries sprocket 192, which through chain 109 is driven from shaft 105, and said shaft, see Figure 5, is driven from motor 103 by reason of the belt 107 that connects the motor pulley and sheave 106 on the shaft 105.

20 The next step in the operation, see Figure 1, is to move the grip finger strip 68, see Figure 15, into contact with the label, to hold the same against the bottle. This is done by the rocking of the walking beam 112, which raises arms 113 and 116 to rock shaft 77 in counter-clockwise direction to swing the grip finger 68 into the position of Figure 15.

In this position, the grip finger shaft 77 is locked by pawl 87 and latch 88; see Figures 12, 30 13 and 14.

The next step is to move pressing fingers 78, see Figure 15, into contact with the label to press the latter against the bottle until the glue adheres. Cam 94 carries an integral sprocket 35 100 which is driven by chain 110, see Figure 6, from shaft 64.

Rotation of cam 94 will actuate roller 96 on arm 97 and rock shaft 86, causing the pressing fingers 78 to be moved against the label as in Figure 15. The mechanism is so timed that the 40 picker arms 52 swing away from the bottle just after the grip finger 68 has gripped the label, so as to make room for the pressing fingers.

A coil spring 83' connects arm 82 of the fingers 78 so that when the pin 92, of Figures 12 and 45 14, moves against latch 88 to release the grip finger, the same will be cushioned by spring 83'. At this time the cam 94 will allow roller 96 to drop so that the grip finger and the pressing fingers will retract together and the latch 88 will again be locked.

As the picker arms begin to swing back to the label holder 24, it is desired to provide their face plates 53 with another coating of glue. To effect this, it is necessary to release glue transfer roll 49 from latches 54, as in Figures 1 and 6. The rod 123 being connected to beam 112, it is apparent that stop 125 will contact lug 120 to rock shaft 119 and lift rod 121. This action will raise latches 54 and release the glue transfer roll 49, which will swing down into contact with plates 46, by reason of the energy stored up in spring 128, see Figure 5, fixed to the frame at 60 129 and to arm 130 of shaft 55. This movement is damped by a dash-pot mechanism, as follows: at an intermediate point the rod 131 is pivoted to arm 130 and extends into cylinder 132 where it is provided with a piston 133. A valve 134 acts as a bleeder.

70 Thus it may be seen that the glue transfer roller 49 is held against plates 46 with a steady, uniform pressure while the glue is being transferred. The glue roller 49 is rotated continuously by sprocket 61 and chain 109, see Figure 6.

75 While I have described a preferred embodiment

of my invention, it is obvious to those familiar with the art that numerous changes and modifications may be made to adapt the machine to various sizes and shapes of bottles or other containers to be labeled. I reserve the right to 5 make all changes permitted within the spirit of my invention and the scope of the following claims.

Having thus described my invention, what I claim and desire to secure by Letters Patent is: 10

1. A labeling machine comprising a support for a supply of labels, a support for a container to be labeled, means for transferring labels, one at a time, from the one support to the other, an adhesive fountain, a roller, means to move the roller from a position in which it obtains a supply of adhesive from the fountain to a position in which it applies adhesive to the label transferring means, the transferring means being arranged to maintain the roller in adhesive 20 obtaining position with respect to the fountain when said transferring means is in position to obtain a label from the supply of same, and mechanism to operate the label transferring means and to move the roller from the fountain 25 to apply adhesive to the transferring means prior to the engagement of the next label by the transfer means.

2. A labeling machine comprising a support for a supply of labels, a support for a container to be labeled, means for transferring labels, one at a time, from the one support to the other, an adhesive fountain, a roller, means to move the roller from a position in which it obtains a supply of adhesive from the fountain to a position in 30 which it applies adhesive to the label transferring means, a cam to maintain the roller in adhesive obtaining position with respect to the fountain when said means is in position to obtain a label from the supply of same, and mechanism to operate the label transferring means and to move the roller from the fountain 35 to apply adhesive to the transferring means prior to the engagement of the next label by the transfer means. 40

3. A labeling machine comprising a support for a supply of labels, a support for a container to be labeled, pivotally mounted means for transferring labels from the one support to the other, an adhesive fountain, a roller, means to move the roller from a position in which it obtains a supply of adhesive from the fountain to a position in which it is in the path of said means when the latter moves from the container support to the label support, mechanism to swing 50 said means pivotally from the container support to the label support, whereby adhesive is applied from the roller during such movement, and said means being arranged to move the roller toward its adhesive obtaining position with 55 respect to the fountain and means to maintain the roller in said position until the next cycle of operation, said mechanism subsequently swinging the transfer means from the label support to the container support, and means to apply a 60 label to the container. 65

4. A labeling machine comprising a support for a supply of labels, a support for a container to be labeled, means for transferring labels from the one support to the other, an adhesive fountain, 70 an adhesive transferring element, means to move said element from a position in which it obtains adhesive from the fountain to a position in which it applies adhesive to the label transferring means, spring means tending to move said ele- 75

- ment from its position in which it obtains adhesive from the fountain to its position in which it applies adhesive to said means, latch means restraining said element from moving to its adhesive applying position while said means transfers a label from the supply thereof to the container support, mechanism to withdraw the latch means to permit said element under the influence of the spring to move to an adhesive applying position 5 with respect to said means when said means is in its return movement to obtain another label, and mechanism to move the label transferring means back and forth between the supports.
5. A labeling machine comprising a support 10 for a supply of labels, a support for a container to be labeled, means for transferring labels from the one support to the other, an adhesive fountain, an adhesive transferring element, means to move said element from a position in which it obtains adhesive from the fountain to a position in which it applies adhesive to the label transferring means, spring means tending to move said element from its position in which it obtains adhesive from the fountain to its position in which 15 it applies adhesive to said means, latch means restraining said element from moving to its adhesive applying position while said means transfers a label from the supply thereof to the container support, mechanism to withdraw the latch means to permit said element under the influence of the spring to move to an adhesive applying position 20 with respect to said means when said means is in its return movement to obtain another label, mechanism controlling the action of the spring during its operation, and mechanism to move the label transferring means back and forth between the supports.
6. A labeling machine comprising means to supply labels from a source of supply to successive 25 containers, an adhesive fountain, means to transfer adhesive from the fountain to the labels successively, said means including a plate to apply adhesive to the labels and a roller to transfer the adhesive from the fountain to the plate, the roller being movable from the fountain to roll across the plate, means tending to move the roller away from the fountain, and releasable means maintaining the roller at the fountain until the plate is ready to have a fresh supply of adhesive applied thereto.
7. A labeling machine comprising means to supply labels from a source of supply to successive containers, an adhesive fountain, means to transfer adhesive from the fountain to the labels successively, said means including a plate to apply adhesive to the labels and a roller to transfer the adhesive from the fountain to the plate the roller being mounted to swing about an axis from the fountain and roll across the plate, the axis of the swinging movement of the roller being above and out of the vertical plane of the part of the fountain engaged by the roller, whereby the roller tends to swing by gravity away from the fountain, and releasable means maintaining the roller at the fountain until the plate is ready to have a fresh supply of adhesive applied thereto.
8. A labeling machine comprising means to supply labels from a source of supply to successive containers, an adhesive fountain, means to transfer adhesive from the fountain to the labels successively, said means including a plate to apply adhesive to the labels and a roller to transfer the adhesive from the fountain to the plate, means to move the roller from the fountain to the plate, and releasable means maintaining the

roller at the fountain until the plate is ready to have a fresh supply of adhesive applied thereto.

9. A labeling machine comprising means to supply labels from a source of supply to successive containers, an adhesive fountain, means to transfer adhesive from the fountain to the labels successively, said means including a plate to apply adhesive to the labels and a roller to transfer the adhesive from the fountain to the plate, spring means tending to move the roller from the fountain to the plate, and releasable means maintaining the roller at the fountain until the plate is ready to have a fresh supply of adhesive applied thereto. 5

10. A labeling machine comprising a movable support for a supply of labels, a support for containers, means to transfer labels successively from the supply thereof to containers on the support, means to affix to containers labels so transferred, said means being mechanically connected for continuous operation, spring means tending to move the supply of labels away from the sphere of operation of the transfer means, and mechanism operable by the operator to overcome the spring means and move the supply of labels to a position in which they may be transferred successively to containers on the support. 10

11. A labeling machine comprising a support for a supply of labels, a support for a container to be labeled, means for transferring labels from the one support to the other, an adhesive fountain, an adhesive transferring element, means to move said element from a position in which it obtains adhesive from the fountain to a position in which it applies adhesive to the label transferring means, mechanism restraining said element from moving to its adhesive applying position while said first-mentioned means transfers a label from the supply thereof to the container support, means to render said restraining mechanism ineffective, and means to thereupon move said element to an adhesive applying position with respect to said first-mentioned means in its return movement to obtain another label. 15

12. A labeling machine comprising a support for a supply of labels, a support for a container to be labeled, means for transferring labels from the one support to the other, an adhesive fountain, an adhesive transferring element, means to move said element from a position in which it obtains adhesive from the fountain to a position in which it applies adhesive to the label transferring means, mechanism restraining said element from moving to its adhesive applying position while said first-mentioned means transfers a label from the supply thereof to the container support, means to render said restraining mechanism ineffective, and spring means to thereupon move said element to an adhesive applying position with respect to said first-mentioned means in the latter's return movement to obtain another label. 20

13. A labeling machine comprising a support for a supply of labels, a support for a container to be labeled, means for transferring labels from the one support to the other, an adhesive fountain, an adhesive transferring element means to move said element from a position in which it obtains adhesive from the fountain to a position in which it applies adhesive to the label transferring means, mechanism restraining said element from moving to its adhesive applying position while said first-mentioned means transfers a label from the supply thereof to the container support, means to render said restraining mecha- 25

nism ineffective, tensioned spring means to there-upon move said element to an adhesive applying position, with respect to said first-mentioned means in the latter's return movement to obtain another label, and means to retard the release of tension in said spring means.

14. A labeling machine comprising a support for a supply of labels, a support for containers, mechanism to transfer labels successively from

the supply thereof to containers on the latter support, means to affix to containers the labels transferred, said mechanism being mechanically connected for continuous operation, means urging said label support to an inoperative position with respect to the removal of labels therefrom, and releasable means to render the label support operative at will.

GEORGE M. BINER.
